ACOUSTIC DEVICE

Lee T. Smith, Madison, N. J., and Albert L. Thurias, New York, N. Y., assignors to Bell Telephone Laboratories, Incorporated, New York, N. Y., a corporation of New York

Application April 25, 1934, Serial No. 722,266

7 Claims. (Cl. 181—32)

This invention relates to acoustic devices, and more particularly, to diaphragms for transmitters or microphones.

In a telephone transmitter or microphone, it is desirable to have a diaphragm that is substantially non-hygrosopic, that will not be substantially affected by variations in atmospheric temperatures, that is low in density and in mechanical stiffness, that may be shaped to and 10 retain a desired contour, and that is flame-resistant.

An object of this invention is to satisfy the need for such a diaphragm.

A feature of this invention comprises a diaphragm of polymerized styrol.

A more complete understanding of this invention will be obtained from the detailed description which follows, read with reference to the appended drawing, wherein:

20 Fig. 1 is a cross-sectional view of a fragment of an acoustic device embodying this invention; and

25 Fig. 2 is a perspective view of a diaphragm embodying this invention, partly broken away and partly in section.

A diaphragm of polymerized styrol may be made by pressing the solid material into shape; or, by first dissolving the solid material in a suitable solvent, for instance, benzene, toluene, 30 ethylene dichloride, trichlorethylene, or the like, and the spraying, brushing, dipping, or spinning it onto a plane surface, allowing the solvent to evaporate to leave the material in sheet form. Polymerized styrol may be obtained on the market under the names of "Meta- 35 Styrene", "Victron" and "Resoglas".

When the spinning method is employed, the solution is poured on a revolving plane surface, 40 preferably glass, on which it spreads to a thickness dependent upon the viscosity of the solution, the rate of rotation of the surface, and surrounding atmospheric conditions. A continuous process similar to that used in the manufacture of motion picture films from solutions of cellulose nitrate or cellulose acetate 45 may be used, also.

A diaphragm of a particular configuration, for instance, one having a central stiffened portion, an outer peripheral portion, and an intermediate portion connecting the outer and the central 50 portions and permitting the central portion to vibrate substantially as a whole in response to impulses of sound wave frequency, may be obtained by operating on the polymerized styrol sheet with suitably shaped dies.

The drawing shows a fragment of an electrodynamic type transmitter or microphone 10, comprising a casing 11 providing an enclosure for a magnet structure 12, which supports a diaphragm 13 embodying this invention.

The magnet structure comprises a center pole 14, for instance, of cobalt iron, having a dome-shaped or cap member 15, for instance, of magnetic iron, secured thereto by any suitable means, for instance, bolt 16, and an outer pole 17, for instance, of cobalt steel. A plate pole 18, 10 preferably annular, of magnetic iron and forming an annular air gap 19 with the member 15, is supported on the outer pole, and has a peripheral, upwardly extending flange or ledge 15 portion 20.

The diaphragm 13 is formed, preferably, from a sheet of polymerized styrol of substantially uniform thickness. A diaphragm as thin as .001 to .0011" and of outside diameter of approximately 1" has been found to give satisfactory results. Such a diaphragm is substantially non-hygrosopic and unaffected by atmospheric temperature variations, is low in density and in mechanical stiffness, may be readily and permanently shaped to a desired contour, and is flame-resistant. The diaphragm comprises a central, stiffened, dome-shaped portion 21 of shape similar to that of the upper surface 22 of the member 15; an outer peripheral and 20 annular portion 23, adapted to be mounted on and secured by a suitable adhesive to the ledge portion surface 24; and an intermediate curved, outwardly concave portion 25, connecting the outer and central portions and being adapted 30 to permit the portion 21 to vibrate substantially as a unit or piston, in response to impulses of sound wave frequency. A coil 26 is attached to the underside of the diaphragm at the narrow, annular, planar portion 27 connecting the central and intermediate portions, and is disposed in the air gap 19. Member 28 is a damping plate attached to the cap member by screws 29 (one only being shown), and providing a narrow restricted passage 30 connecting the air 35 spaces or chambers 31, 32 through the air gap 19 with the air space or chamber 33 in the magnet structure. Sound wave energy has access to the diaphragm through the apertures 34 in the casing.

Although this invention has been described with reference to a specific embodiment thereof, it will be understood that it is capable of other forms and sizes without departing from the spirit of the invention, which is to be con- 55

sidered as limited in scope, therefore, by the appended claims, only.

What is claimed is:

1. An acoustic device comprising a diaphragm of polymerized styrol.
2. An acoustic device comprising a diaphragm of polymerized styrol of substantially uniform thickness throughout.
3. An acoustic device comprising a diaphragm of polymerized styrol having a central stiffened portion.
4. An acoustic device comprising a diaphragm of polymerized styrol having a central stiffened portion, a peripheral mounting portion, and an intermediate portion connecting the peripheral and central portions and allowing the central portion to vibrate substantially as a whole in

response to impulses of sound wave frequency.

5. An acoustic device comprising a diaphragm of polymerized styrol of a thickness of about .001 to .0011".

6. An acoustic device comprising a diaphragm of polymerized styrol substantially 1 mil in thickness throughout, having a central stiffened portion, a peripheral mounting portion, and an intermediate portion connecting the peripheral and central portions.

7. An acoustic device comprising a diaphragm of polymerized styrol having a central stiffened portion and being substantially 1 mil in thickness throughout.

LEE T. SMITH.
ALBERT L. THURAS.
